UNITED STATES PATENT OFFICE

117,986

DESIGN FOR A BOX OR SIMILAR ARTICLE

Albert S. Weiss, Cleveland, Ohio

Application October 5, 1939, Serial No. 87,520

Term of patent 7 years

To all whom it may concern:

Be it known that I, Albert S. Weiss, a citizen of the United States of America, residing in the city of Cleveland, county of Cuyahoga, and State of Ohio, have invented a new, original, and ornamental Design for a Box or Similar Article, of which the following is a specification, reference being had to the accompanying drawing, forming part thereof.

Fig. 1 is a front perspective view of a box or similar article showing my new design.

Fig. 2 is a top plan view of the box on a somewhat larger scale.

Fig. 3 is a rear view of the box.

The bottom view of the box is the same as Figure 3.

I claim:

The ornamental design for a box or similar article, substantially as shown and described.

ALBERT S. WEISS.
